UNITED STATES PATENT OFFICE.

GEORGE B. KINSLER, OF HARTFORD, CONNECTICUT, ASSIGNOR TO THE KINSLER-BENNETT COMPANY, OF HARTFORD, CONNECTICUT, A CORPORATION OF CONNECTICUT.

UNIVERSAL JOINT.

980,966.

Specification of Letters Patent. Patented Jan. 10, 1911.

Application filed May 6, 1910. Serial No. 559,734.

To all whom it may concern:

Be it known that I, GEORGE B. KINSLER, a citizen of the United States, residing at Hartford, in the county of Hartford and State of Connecticut, have invented certain new and useful Improvements in Universal Joints, of which the following is a specification.

This invention relates to universal joints and a device involving my invention can be used with advantage in many different connections.

One of the purposes of the invention is to provide a joint which is thoroughly strong. Another object is to provide for long life thereof and a further one is a means for firmly holding in position the divided rings or clamps which are generally utilized to hold the terminal members of the cover or casing in place.

The apparatus involves other features of novelty and advantage, which with the foregoing will be set forth at length in the following description wherein I will outline in detail that form of embodiment of the invention which I have selected for illustration, in the drawings accompanying and forming part of the present specification. From the statement just made it will be understood that I do not restrict myself to the showing made by said drawings and description; I may depart materially therefrom within the scope of my invention as expressed in said claims. I also wish to indicate that it is not essential that all the improvements be used in a joint.

Referring to said drawings: Figure 1 is a longitudinal sectional view of a joint involving my invention. Fig. 2 is an end view partly in section of the same, and, Fig. 3 is a detail view of the coupling member of the device.

Like characters refer to like parts throughout the several figures.

My joint comprises three main members as 2, 3, and 4, the members 2 and 3 being practically duplicates and the member 4 constituting a coupling, the coupling member serving through the aid of certain parts for uniting the two members 2 and 3 for relative swinging movement about transverse axes whereby the desired relative universal movement of either or both of said members 2 and 3 can be secured. It does not matter which of the members 2 and 3 is the

driving or power applying one. The members 2 and 3 are shown provided at their inner ends with forks each denoted by 2' and which are as customary disposed at right angles to each other, said forks being so mounted that each branch or arm thereof is supported upon opposite sides of the same whereby a strong structure is assured. The coupling member 4 is of such character as will hereinafter appear, as to provide for thus supporting the two forks.

The two members 2 and 3 may be connected with the intermediate coupling member in any desirable manner, although the means shown for this purpose will be herein-after described. The coupling member includes a body as 6, and although it is conceivable that this body, except for certain slots hereinafter described, might be solid or imperforate, I prefer for the sake of lightness to make it in the form of a skeleton or spider like plate. The body 6, as shown, has four substantially radially disposed arms and a central opening, this relation assuring the desired lightness without sacrificing strength. The body or plate 6 which is preferably integral has four equidistantly disposed slots 7 which are preferably formed in and extend entirely through the arms to which I have already alluded. These slots receive hubs as 3' at the outer ends of the branches of the two main members 2 and 3. These hubs fit the slots somewhat closely transversely thereof, so that said hubs will be supported at their opposite sides, although the slots are somewhat elongated which permits free oscillation of the two members 2 and 3 about their axes. Any lateral movement of the two said members 2 and 3 is effectually prevented while they are laterally supported and braced. The hubs 3' inclose removable bushings 9 and these bushings receive pivots as 10 which may, as shown, consist of pins extending through bores in the plate or body 6 and also through the rim or flange portion 11 surrounding said plate. While it is not essential, I prefer to make this plate in one piece and to also make it integral with the rim or flange 11 as thereby the maximum strength and rigidity are secured. The pivots 10 are preferably stationary, and they are removably held in place by pins as 12 which extend through transverse perforations or holes in the coupling member 4

and pivots 10 respectively. Owing to the fact that the pivots 10 do not turn, they are not subjected to unusual wear which would be the case were they to rock in their bearings. The bushings 9 take up the wear, and as said bushings are removable, it becomes a simple matter to remove the worn parts or any one of them by withdrawing the necessary holding pins 12 and then pulling out 10 the pivots 10 and bushings 9 as required. These pins 12 in addition to holding the pivots 10 in place perform another function as I will hereinafter point out.

The different parts of the joint are preferably inclosed in a cover or housing and this housing may consist of a central portion as 13 and two end or terminal portions as 14. All of these parts are usually spherical, the central portion generally consisting of two 20 sections which overlie the rim or flange 11 and are connected to each other in some suitable manner, for instance, by the pins 12 to which I have referred and which may consist of bolts. The two parts of the central 25 portion 13 are closely fitted to and over the peripheral portion of the rim or flange 11 so that said central portion is rigid with said rim. Owing to the fact that the flange or rim 11 is circular, it practically acts as part 30 of the cover or casing in that it closes the gap between the adjacent edges of the two parts of the central portion 13. There is no direct or positive connection between the terminal sections 14 of the casing or housing and the central part thereof, owing to the fact that said terminal portions have a universal contact with the said central or intermediate portion.

I provide means for rigidly holding the 40 terminal casing sections 14 to the respective members 2 and 3 and if this means is described in connection with one, it will apply to the other, as the same are of similar construction, and in this connection reference will be had to the member 2 and its immediate spherical casing section 14. At 45 the junction between the fork and shank of said driving member 2 there is shown an annular shoulder 16 against which fits the flattened portion 17 of the co-operating part 14, said part 14 being held to the member 2 by being pressed against the said shoulder 16, and for this purpose the divided collar 50 or clamp 18 may be provided, said clamp fitting against the circular flange 19 on the shank or shaft portion of the said member 2, and the parts thereof being connected together by screws 20. It is conceivable that this collar might be threaded onto the shank 60 or shaft portion of said driving member 2, but this is not very desirable in that the collar in such a case will back off, thereby permitting the co-operating casing portion 14 to loosen, and hence rattle. It is also 65 possible that in the construction which I em-

ploy, the screws 20 may be loosened, but I provide a means which will prevent the collar from being turned to any annoying extent even should nuts of its securing bolts 20 be accidentally loosened. This construction I obtained in the present case, by wedging the collar in position, for example, between the flange 19 and the co-operating casing portion 14. The flange 19 has on its inner side a wedge or taper face 21 which operates with a wedge or taper face 22 of substantially similar pitch upon the outer side of the clamp 18. When the clamp is drawn closed by the action of its screws 20, the collar or clamp 18 is most firmly wedged in place, and as said collar bears against the part 14, the latter will be solidly pressed against its seat on the shoulder or bearing 16. I prefer that the internal diameter of the collar or clamp 18 be greater than the 75 external diameter of that part of the shank or shaft portion of the member 2, between the shoulder 16 and the flange 19 so as to amply compensate for any wear and at the same time avoid the necessity of skilled 80 labor in assembling the parts.

What I claim is:

1. A universal joint comprising a pair of members, a coupling member, pivots, supported by the coupling member and connecting said first mentioned member for relative universal movement, a cover device, in sections fitted to the coupling member, and pins for removably holding the sections of the cover device in place and for holding said pivots in position.

2. A universal joint comprising two members having forks disposed approximately at right angles to each other, each branch of each fork having a hub, a coupling member 95 comprising a body and an annular rim, said body having four equidistantly disposed slots in which said hubs fit, bushings removably disposed in said hubs, pivots fitting in said bushings, the coupling member 105 being bored to receive the respective pivots, a cover device in sections fitted to the said rim, and bolts for connecting the sections of said cover device, the coupling member and pivots having perforations through which 110 said bolts pass.

3. A universal joint comprising a pair of members, a coupling member, pivots connecting the coupling member with the first mentioned pair of members, a cover, and pins for removably holding the cover in place and for also holding the pivots in position.

In testimony whereof I affix my signature in presence of two witnesses.

GEORGE B. KINSLER.
